GEORGE VEENHUYZEN, OF ZWYNDRECHT, NETHERLANDS, ASSIGNOR TO THE FIRM
FRIED. KRUPP GRUSONWERK AKTIENGESELLSCHAFT, OF MAGDEBURG-BUCKAU,
GERMANY

PRESS FOR THE TREATMENT OF MOIST MATERIALS

Application filed February 4, 1928, Serial No. 251,933, and in Germany February 5, 1927.

This invention relates to presses, particularly worm presses, for the treatment of moist materials, for instance oil containing materials, of the kind in which the material 5 is continuously passed through a pressing chamber narrowed towards the discharge end, and the oil or other fluid expressed escapes through the walls of the pressing chamber.

- 10 Presses of this kind with pressing chambers narrowing toward the discharge end have been built heretofore, in which either the pitch of the worm thread has been decreased or the worm shaft diameter increased 15 towards the discharge end of the press. This has certain disadvantages, especially because of increased friction, which disadvantages are overcome by the present invention.
- 20 According to the invention the pressing chamber comprises a series of compartments of progressively reduced diameters connected by tapering passages, the oblique internal surfaces of which passages have a damming 25 action on the material passing from one compartment to the next. The thread of the worm is interrupted at the tapering passages so that the material progresses in these parts, where it passes from a certain chamber 30 to the next chamber of a higher pressure, in a straight axial direction. This circumstance, as well as the fact, that the surfaces exposed to friction decrease in this press with increasing pressure, very appreciably 35 improve the usefulness of a press of this kind.

In order that the said invention may be clearly understood and readily carried into effect, the same will now be described more 40 fully with reference to the accompanying drawings, in which:—

Figure 1 represents in longitudinal section a worm press exemplifying this invention.

45 Figure 2 represents a vertical section taken on the line A—B in Figure 1.

In the length of the main pressing chamber or strainer 1 there are several compartments or constituent pressing chambers, four 50 such compartments being illustrated and re-

spectively marked 2, 3, 4 and 5, these compartments being in this example cylindrical and of different diameters progressively reduced as they approach the discharge end of the press. These compartments are perforated for the escape of the fluid expressed from the material passing through them, and are connected by tapering passages, the oblique walls 6, 7 and 8 of which passages may also be perforated to act as strainers. 55 The pressing device is a worm conveyor 9 which forces the material through the chambers, its threads or blades being preferably situated only in the compartments 2, 3, 4, 5 and in the feed chamber 11, the diameter of the worm thread in each compartment being adapted to the diameter of the particular compartment in which it works. The material to be treated passes from the inlet 10 into the feed chamber 11, the walls 12 of which may be hinged as seen in Figure 2 in order to facilitate access to the interior of the apparatus for cleaning or other purposes. These walls 12 are provided with 60 perforations 13 (Figure 2) for the escape of the oil or other fluid component of the material treated. The said material is passed by the worm 9 from the chamber 11 into the compartment 5 and on reaching the oblique wall 6 is compressed, with simultaneous discharge of fluid through the perforations in the compartment 5. The compressed material is then pushed by the worm 9 into the compartment 4, where its progress is again dammed at the oblique wall 7, so 65 that it is further compressed, then passes into the compartment 3 and is again dammed and compressed at the oblique wall 8, then pushed into the compartment 2 from which it finally escapes through the annular passage 14. 70

The invention is obviously capable of being carried out with several variations, for instance, instead of the strainer or pressing chamber being constructed with perforated walls, it may be made of rods between which the expressed fluid can escape. Instead of the walls of the compartments being cylindrical they may be cylindro-conical. When the pressing device is a worm, the blades 75 80 85 90 95 100

thereof in the different compartments may be of equal sizes, or of different sizes.

It is found that when the apparatus is used for expressing oil, a greater yield of oil and/or a greater capacity is obtained with apparatus embodying this invention than is obtained by the use of a pressing chamber of uniform diameter, or of uniformly decreasing diameter.

10. What I claim is:

1. A press of the character described, comprising a pressing chamber with a plurality of compartments of progressively decreasing average diameters and with perforated walls, 15 said compartments being connected by tapered passages; and a worm with substantially cylindrical shaft, the thread of the worm being discontinued and said shaft being left blank at the passages.
20. 2. A press of the character described comprising a pressing chamber made up of a plurality of compartments of progressively decreasing average diameters, said compartments being connected by tapered passages, 25 a driven shaft, feeding means on said shaft, said feeding means being discontinued and said shaft being left blank at said passages.
3. A press of the character described including a pressing chamber, successive points 30 of maximum pressure and of relatively lower pressure in said chamber, a driven shaft in said chamber, feeding means on said shaft, said feeding means being discontinued and said shaft being left blank at said 35 points of maximum pressure.

The foregoing specification signed at The Hague, Kingdom of the Netherlands, this twentieth day of January, 1928.
